UNITED STATES PATENT OFFICE

IRA E. McCABE, OF CHICAGO, ILLINOIS

ELECTRICAL CONNECTION

Application filed January 17, 1929. Serial No. 333,035.

This invention relates to improvements in electrical connections and more particularly to the construction of binding posts for such connections.

5 In many electrical devices binding posts are employed in making a connection between a lead which is connected as a permanent fixture to the device at the factory and a detachable lead to a source of electricity, which 10 is attached after the device has been installed at its place of operation.

It is an object of this invention to provide a binding post adapted to be fixed upon the device and to which a device lead may be connected by the same means that connects the external lead and secure the device lead in a substantially permanent manner while the external lead may be attached or detached to the same binding post without affecting 20 the connection of the device lead.

With these and other objects in view reference is made to the accompanying sheet of drawings which illustrates the preferred forms of this invention, with the understanding 25 that minor detail changes may be made therein without departing from the scope of the invention.

In the drawings:

Figure 1 is a top plan view of a preferred 30 form of the improved binding post constructed in accordance with this invention.

Figure 2 is a view in side elevation of Figure 1.

Figure 3 is a view partly in vertical longitudinal section through the center of the binding post, or taken on the line 3—3, Figure 4, and partly in side elevation, illustrating a completed connection.

Figure 4 is a view in end elevation of Figure 3 with the leads detached and separated therefrom.

Figure 5 is a top plan view of a modified form of binding post.

Figure 6 is a view in side elevation of Figure 5.

Figure 7 is a view similar to that of Figure 3, taken on the line 7—7, Figure 8.

Figure 8 is a view in end elevation of Figure 7 with the leads detached and separated 50 therefrom.

Figure 9 is a view in elevation of a plurality of binding posts, of the first form illustrating one manner of securing the same in place upon a device, with one post in use.

Figure 10 is a fragmentary top plan view 55 of Figure 9.

Figure 11 is a view similar to Figure 9, of a binding post of the second form.

In Figures 1, 2 and 3 of the drawing, the body 1 of the binding post is shown with a smaller shouldered portion 2 extending to the left with a screw threaded shaft projecting therefrom. The opposite end is countersunk as shown in Figure 3, and, as shown in Figure 4, it is preferable to form the top of the body 1 upon an arc of a circle which is intercepted by parallel opposite sides joined rectangularly to a bottom side. The inner walls of the countersunk portion are formed on the arc of a circle concentric with said first circle, which provides a flange 4 about the two flat sides and adjoining curved top, leaving the countersink open across the flat bottom side. The flange 4 is cut away to form a slot 5 from where it joins the main body 1 to a distance substantially one-half its height and extending about the curved top and a short distance down each flat parallel side, as shown in Figures 1 and 2.

A screw threaded well 6 is sunk in the main body, as shown in Figure 3, concentric with the circular flange, which is adapted to receive a correspondingly screw threaded binding member preferably in the form of a headed screw 7, the head 8 of which may be received within the circular inner walls of the flange 4.

Figure 3 illustrates a connection between a device lead 9 and an exterior lead 10. It is customary to form a terminal lug which will ordinarily form a fixed connection in the form of a flat perforated disc, such as 9^a as shown in Figure 4, and a temporary connection is usually formed by stripping the lead of its insulation and bending the uncovered metal wire in the form of a loop 10^a, as shown in Figure 4, to provide a terminal lug formed of a flat perforated metal disc 10^b in which the body is slit between the per-

foration and the circumference, as shown in Figure 8.

In making the connection, the terminal lug 9* of the device lead 9 is inserted through the slot 5 and the screw 7 passed through the perforation thereof and engaged in the screw threaded well 6 of the binding post. When it is desired to complete the connection to the external wire, the end of the wire 10 is bent, as shown in Figure 4, and hooked about the screw 7, the main body of the wire passed between the open ends of the flange 4, and the screw 7 rotated until the under side of its head 8 engages and firmly holds the 15 terminals of the leads 9 and 10 against each other and against the flat base of the counter sink in the body 1.

Figures 9 and 10 show one means of securing a plurality of binding posts, of the 20 form just described, to the casing 20 of an electrical device which means comprises a plate of insulation material 11 having a plurality of apertures formed therein through which the shouldered portions 2 of the posts 25 1 are passed and held in engagement therewith by the nuts 12 engaging the screw threaded portions 3 of the posts. When the posts 1 are formed of metal, as is usual, they are preferably insulated from the customary 30 metal casing 20 and each other by providing shouldered partitions 13 of insulation material passed through slots in the plate 11 with the shoulders engaging the under side thereof and spacing the plate 11 a sufficient distance 35 from the casing to clear the nuts 12. It is also preferable to cover the portion of the casing below the binding posts with a sheet of insulation material 14 and secure the binding posts bearing plate 11 to the casing 20 40 by a bolt or screw 15 passing through a block of insulation material 16, the plate 11, the sheet 14 and engaging the casing 20. It is preferable to arrange the posts in staggered relation, as shown in Figure 10, with the partitions 13 in engagement with flat sides of the posts. When so arranged the partitions 45 not only secure the posts against rotation, insulate the posts from each other, but also prevent any contact between the adjoining leads 50 connected to the respective posts.

The type of post illustrated in Figures 5, 6, 7 and 8 differs only from the one just described in the means provided for attaching upon the device casing. In this type it is 55 preferably to form the main body 1 cylindrical, the base with an outstanding flange 21, and the portion of the body opposite the slot 5 cut away to form a flat side 22. When employing this type, the plate of insulation material 11 is provided with apertures corresponding in shape and size to the body of the post, the posts are inserted therethrough from the under side until the flanges 21 engage the plate 11 and then the plate 60 secured to the casing 20 with a sheet of in-

sulation material 14 interposed between the casing 20 and bottom of the flanged portion 21 of the posts. The shape of the posts prevents rotation when so secured.

While it is preferable to form the binding 70 posts of metal, for ease of manufacture, as the first form is readily turned from square stock and the second form from cylindrical stock, yet the posts may be formed of insulation material without departing from the 75 scope of this invention. Likewise the posts may be attached or secured in any deserved manner to the device casing.

From the description of the construction and application of this improved binding 80 post, it is readily seen that, when such a post is made a part of an electrical device, a lead from the device may be connected thereto at the factory in a semi-permanent manner by inserting the perforated lead terminal lug, 85 or the looped end of the wire from which the insulation has been stripped, through the slot in the flange about the counter sunk end and then inserting the binding screw 7, the lead will become a non-detachable part of the 90 binding post until it is desired to complete the connection from the device, through the post, to an external wire. Then, it is only necessary to rotate the binding screw in reverse direction sufficiently to allow the lead terminal or terminal lug of the external wire to be inserted through the opening in the flange on the flat side to engage the binding 95 screw, and the screw rotated until its head firmly binds the ends of the two leads together, and the connection is completed, the upstanding flange extends above the connection and not only assists in positioning the terminals therein but is a measure of protection.

What I claim is:

1. An electrical connection for lead wires comprising a post provided at one end with an upstanding flange having a portion of the flange cut away and having a slot formed in the flange adapted to receive a terminal lug, and a binding screw adapted to secure a terminal lug, when so inserted, to the post.

2. An electrical connection for lead wires comprising a post having one end counter sunk to form a flange, said flange cut away at one side and the side opposite provided with a slot adapted to receive a terminal lug, and a binding screw engaging the body adapted to secure a terminal lug, when so received, to the post within the flange.

3. An electrical connection for lead wires comprising a binding post having one flat side and provided at one end with means for securing the same and at the other end with a flange extending therebeyond but cut away above said flat side, said flange provided with a slot opposite said cut away portion, adapted to receive a terminal lug, and a binding screw adapted to engage said post and secure a ter-

terminal lug, when inserted through said slot, and having a head adapted to enter within said flange.

4. An electrical connection for lead wires comprising a binding post having a flat side, provided at one end with means for securing the same and having a counter sink at the other end forming a flange in prolongation of the post except on the said flat side, a slot provided in the flange opposite the opening above the said flat side adjacent the body of the post, adapted to receive a terminal lug, and a binding screw in engagement with the said body of the post, adapted to secure a terminal lug when inserted through said slot, and having a head adapted to be received within said flange.
